UNITED STATES PATENT OFFICE.

EDWARD H. REMDE, OF CLEVELAND, OHIO, ASSIGNOR TO BAKER-RAULANG COMPANY, OF CLEVELAND, OHIO, A CORPORATION OF OHIO.

AUTOMATIC CIRCUIT-CONTROLLING MECHANISM.

Application filed February 13, 1922. Serial No. 536,296.

This invention relates to a mechanism for opening and closing an electric circuit and for controlling the same to prevent its closing, except when the current controlling device (such as a controller) is in neutral position.

One object of the invention is to provide an improved mechanism of this character of relatively simple construction.

10 Another object of the invention is to provide a mechanism of the character in which the operating elements are positively and readily operated to insure complete and speedy operation at all times.

15 Another object of the invention is to provide an improved circuit opening and closing mechanism in which a reciprocating member, controlled by a plurality of cams, causes the engagement and disengagement of 20 a pair of contact elements to open and close an electric circuit.

Other objects of the invention will be apparent to those skilled in the art to which my 25 invention relates from the following description taken in connection with the accompanying drawings.

In the drawings, Fig. 1 is a side elevation of a vehicle which carries an electric motor, the circuit for which is controlled 30 by a mechanism embodying my invention.

Fig. 2 is a fragmentary side elevation of the vehicle and my circuit opening and closing mechanism shown in Fig. 1, parts being broken away and a portion of the vehicle 35 being shown in dotted lines.

Fig. 3 is a fragmentary front view of the circuit opening and closing mechanism, a portion of the vehicle being shown in dotted lines.

40 Fig. 4 is a top plan view of the parts shown in Fig. 2.

Fig. 5 is a top plan view, enlarged, of the opening and closing mechanism.

Fig. 6 is a section on the line 6—6 of Figs. 45 4, 5 and 8.

Fig. 7 is a section similar to Fig. 6, but showing the elements operated to the circuit closing position.

50 Fig. 8 is a section on the line 8—8 of Fig. 6.

Fig. 9 is a section on the line 9—9 of Fig. 6.

Fig. 10 is a fragmentary elevation on the line 10—10 of Fig. 6.

65 Fig. 11 is a view similar to Fig. 10, but

showing the elements in the position assumed when the controller has been operated but the circuit is open.

Fig. 12 is a fragmentary section on the line 12—12 of Fig. 11.

Fig. 13 is a fragmentary section similar to Figs. 6 and 7, but illustrating the position of the elements when the controller is "on" and attempt is made to close the circuit.

I have by preference, shown my invention 65 as applied to an electrically driven vehicle, for example, an industrial truck, and adapted it for controlling the circuit to the motor which drives the traction wheels therefor, but it will be obvious that the mechanism 70 may be interposed in any electric circuit, whether the same forms a part of a mechanism for or associated with a vehicle or not.

In the drawings, 1 indicates the frame of the vehicle. 2, 2', indicate the wheels for the 75 truck, there being four wheels by preference. Either or both pairs of wheels 2, 2', may be steered by a lever 3 through suitable operating connections.

4 indicates a platform on which the operative who operates the vehicle, may stand. The platform is connected to the frame 1 in any desired manner.

5 indicates an electric motor connected to and transmitting power through a power 85 mechanism 5' to drive the wheels 2.

6 indicates the battery or batteries for supplying current to the motor 5.

7 indicates a braking mechanism, preferably including a band 7^a positioned to engage a band wheel 7^b fixed to an extended end 5^a of the power transmitting shaft of the power mechanism 5', whereby the wheels 2 will be locked against movement when the band 7^a engages the wheel 7^b. The band 7^a 95 is connected to one arm of a bell crank 7^c.

8 indicates a member pivotally mounted on the frame 1 and connected to the other arm of the bell crank 7^c, whereby the band 7^a may be applied to or released from the 100 band wheel 7^b, at will.

9 indicates a spring preferably connected to one arm of the crank 7^c, or some element connected thereto (for example, the link 14) and some fixed part of the motor 5 or frame 1. By preference, the spring 9 is so connected to the crank 7^c that it will normally tend to apply the brake band 7^a; accordingly if the member 8 is released by the operative the spring 9 will automatically ap- 110

ply the brake. The connections between the member 8 and crank 7^c preferably comprise a tail piece 10 fixed to the rock shaft 11 for the member 8, a link 12 connected to the tail piece 10 at one end and at its other end connected to a lever 13, and a link 14 connected to the lever 13 at one end and at its other end connected to one arm of the crank 7^c, as already described. 14^a indicates a projection on the lever 13. The projection 14^a is arranged to engage some fixed stop, for example the adjacent frame member 1^a of the frame 1, as shown in Figs. 1, 2 and 3. By preference, the brake operating member 8 comprises a foot pedal which the operative can manipulate with one foot in one direction, against the tension of the spring 9 to release the brake mechanism 7, this pedal being so arranged that the operative 20 can hold it in operated position while standing on the platform 4. 15 indicates a controller of any suitable construction. 15' indicates a lever, operating through a rod 16 and arm 17 to operate the controller 15 in either direction, whereby the motor may be controlled to drive the wheels 2 forwardly or backwardly.

My improved circuit controlling or opening and closing mechanism is interposed mechanically between the brake operating member 8, the brake mechanism 7 or one element of the operating connections for the latter, (preferably the lever 13) and the controller 15, and is operatively connected thereto, whereby the circuit may be controlled in the manner hereinafter set forth.

18 indicates a casing or box-like member adapted to be fixed in any desired manner to the dash or other part of the vehicle frame 1. 40 19 is a cover for the casing 18 removably held in position by a plurality of screws or other devices 19^a.

20 indicates a base of insulating material fixed to the back wall 18^a of the casing 18. 45 The base preferably comprises a layer of micanite 20^a and a layer of ebony asbestos board 20^b.

21, 22, indicate a pair of terminals, fixed to the base 20 by screws 21^a, 22^a respectively, 50 as shown in Figs. 8 and 9. The terminal 21 is adapted to have connected to it a lead (not shown) from the battery or batteries 6, an opening 23 being formed in the bottom wall 18^b to accommodate the lead; whereas the terminal 22 is adapted to have connected to it a lead (not shown) connected to the controller 15, an opening 24 being formed in the bottom wall 18^b to accommodate the lead. The terminal 22 is fashioned or 60 shaped to provide a contact 25 with which a movable contact 26 engages to close the circuit from the battery or batteries 6 to one terminal of the controller 15 through the leads just referred to and disengages to open 65 said circuit. The contact 26 is preferably

formed of laminæ. The contact 26 is secured at its upper end to a block (formed of suitable conducting material) 27 having a sleeve 28 which is fixed to but insulated from a reciprocating member 29, which will be 70 later described.

The block 27 is connected with the terminal 21 by a flexible conductor 30, which is long enough to permit movement of the contact 26 and block 27 with the reciprocating 75 member 29.

The conductor 30 is connected to the block 27 and terminal 21 in any desired manner. The reciprocating member 29 comprises a rod which extends through the casing 18, being mounted to slide at its opposite ends in openings 31, 32, formed in thickened portions of the end walls 18^c, 18^d of the casing 18.

The rod 29 has an enlarged portion which 85 is bored out from one end, as shown at 33, for a purpose to be later set forth. The enlarged portion of the rod forms a shoulder against which the sleeve 28 is rigidly clamped by a nut 34. The rod 29 is preferably reduced at its other end, as shown at 35, in which event the nut 34 may be of a size to fit such reduced end and clamp the sleeve 28 without occupying undue space.

36, 37, indicate a pair of coiled springs arranged in the bore 33 of the rod 29 and engaging at their inner ends the opposite sides of a collar 38 fixed on the inner end of a thrust member 39. As shown, the spring 36 is interposed between the collar 38 and the 90 end or bottom wall of the bore 33, whereas the spring 37 is interposed between the collar 38 and a ring 40 removably fixed at or adjacent the outer or open end of the bore 33.

From the foregoing description it will be 105 seen that (1) operation of the thrust member 39 inwardly will compress the spring 36 if the reciprocating member is locked against movement or until its tension overcomes the resistance holding the rod 29 110 against movement in that direction, whereupon the rod will be operated with a relatively quick movement endwise toward the left in Fig. 6, and (2) operation of the thrust member 39 outwardly will compress the spring 37 if the reciprocating member is locked against movement or until its tension overcomes the resistance holding the rod 29 against movement in that direction, 115 whereupon the rod will be operated with a relatively quick movement endwise toward the right in Fig. 6.

The thrust member 39 is connected to and operated in either direction by the lever 13, 120 whereby (1) movement of the member 8 to release the brake 7 will effect a closing of the circuit through the contacts 25, 26, (see Fig. 7) and (2) movement of the member 8 in the opposite direction will effect a separation of the contacts 25, 26, and opening 125 130

of the circuit therethrough (see Fig. 6). The connection between the thrust member 39 and lever 13 preferably comprises the following instrumentalities: 41 indicates a rod 5 pivotally connected at its lower end to a knuckle 41^a provided on the lever 13; at its upper end the rod 41 is pivotally connected to one arm of a bell crank 42; the other arm of the bell crank 42 is bifurcated, and said 10 bifurcations are formed with aligned openings 43 which support the opposite ends of a rocker 44. The rocker 44 is formed with a screw threaded opening whereby it may be adjustably secured upon the outer screw-threaded end of the thrust member 39. The ring 40 is preferably of such size as compared to the size of the thrust member 39 that the latter is free to be moved by the crank arm to which it is connected as it 15 swings in either direction. The crank 42 is pivoted on a short shaft or pin 45, preferably supported by the dash of the vehicle, as shown in Figs. 2 and 4. The rod 29 may have a flattened portion 29^a, (see Fig. 8) 20 with which engages the inner end of a boss 29^{a'} fitting an opening in the wall 18^a to prevent rotation of the rod 29 at any time.

46 indicates as an entirety devices which control the movement of the reciprocating member 29 in correlation to the thrust member. Of these control devices, 47, 48, indicate a pair of plungers slidably mounted in openings 47^a, 48^a, respectively. The upper ends of the plungers slidably fit into recesses 35 47^b, 48^b, respectively, formed in the wall of a supplemental casing member 49. The casing member 49 is preferably fixed to the upper wall 18^a of the casing 18 by screws or other devices 50. The recesses 47^b, 48^b, are 40 provided as a convenient means for supporting springs 51, which normally act to push the plungers 47, 48, downwardly. At their lower ends, the plungers 47, 48, are provided with shoulders 47^c, 48^c, and these shoulders 45 are arranged to engage transverse walls 52, 53, respectively, on the reciprocating rod 29. The transverse locking walls 52, 53, are spaced so that when the rod 29 is at its extreme left position (see Fig. 6) the wall 53 will engage the shoulder 48^c and be locked thereby against movement toward the right; likewise when the rod 29 is at its extreme right position (see Fig. 7) the wall 52 will engage the shoulder 47^c and be locked 55 thereby against movement toward the left.

54 indicates a combined lock and release device slidably mounted in guides 55. The guides 55 preferably consist of slots or openings formed in the end walls of the supplemental casing member 49 and a groove 56 formed in and extending longitudinally of the upper casing wall 18^a, the walls of the slots and grooves being shaped to receive the lock and release device 54. As shown, 60 the guides 55 are preferably disposed in a

plane which extends through or intersects the locking plungers 47, 48; accordingly, the latter are cut-away intermediate their ends as shown at 57, so that the upper end wall 57^a of the cut-away portions will overlie 70 the lock and release device 54. The lock and release device 54 preferably comprises a rod of rectangular shape. The rod 54 is of a length to extend to either side of the casing 18 (1) for connection at one end with 75 the thrust member 39 and (2) for co-operation with elements of a mechanism, indicated as an entirety at 58, which maintains the lock and release device inoperative in the manner and for the reasons to be later 80 set forth.

59, 60, indicate cams provided on the upper face of the rod 54 and arranged to engage the upper end walls 57^a of the cut-away portions 57 formed in the plungers 85 47, 48. The cams 59, 60, are so positioned that when the rod 54 is moved from the position shown in Fig. 6 to the position shown in Fig. 7, the cam 60 will engage the wall 57^a of the plunger 48 and move the 90 latter upwardly in its guides 48^a, thereby releasing the reciprocating member 29, which (as will be later set forth) is being acted upon by the spring 37; likewise upon movement of the rod 54 in the opposite 95 direction back to the position shown in Fig. 6, the cam 59 will, through its engagement with the wall 57^a of the plunger 47, release the latter from the reciprocating member 29. The rod 54 is operated in opposite directions by the thrust member 39 through connections, indicated as an entirety at 61, which permits movement of the thrust member 39 relative to the rod 54 when the latter is locked in an inoperative position 100 or against unlimited movement as shown in Fig. 13, by the mechanism 58. Of the connections 61, 62 indicates a cross-head having openings 63, 64, at its opposite ends to receive the thrust member 39 and rod 54, 110 respectively, as shown in Figs. 3, 6 and 13. The opening 63 is provided with screw threads fitting the screw threads upon the outer end of the thrust member 39, whereby the cross-head may be adjustably secured to 115 the latter; a nut 65 being provided to lock the cross-head in its adjusted position. The opening 64 receives the rod 54 and permits the cross-head to be positioned against a collar or other abutment 66 fixed to the 120 rod 54. 67 indicates a coiled spring surrounding rod 54 and disposed between the cross-head 62 and a nut 68 screw-threaded on the outer end of the rod 54. 69, 70, indicate washers or seat members mounted 125 on the rod interposed between the ends of the spring and the cross-head 62 and nut 68, respectively. The spring 67 acting through the nut 68 normally tends to maintain the collar 66 against the cross-head 130

62. From the foregoing description it will be seen that by reason of the connection 61 between the rod 54 and thrust member 39, the rod 54 will move with the latter when it is operated, unless the rod 54 is maintained inoperative by the mechanism 58, in which event the spring 67 permits the thrust member 39 to move relative to the rod 54.

Figs. 1 and 6 illustrate the position of the contacts 25, 26, the reciprocating member 29, the rod 54, lever 42, pedal 8, brake mechanism 7 and the connections between the lever 13 and lever 42 when the vehicle is standing still and ready for an operative 10 to operate the truck. To operate the truck, the operative steps on the pedal 8 and moves it to the position shown in dotted lines in Fig. 1. This operation releases the brake band 7^a and, through the rod 41 and lever 15 20 42, moves the thrust member 39 toward the right in Fig. 3. The thrust member 39 through the cross-head 62, spring 67 and nut 68, in turn moves the rod 54 with it and compresses the spring 37. The cam 60 25 engages the wall 57^a of the plunger 48 and releases the latter from the adjacent wall 48^c, whereupon the spring 37 operates the reciprocating member with a relatively quick movement to the position shown in 30 Fig. 7, thereby moving the contact 26 into engagement with the contact 25 and closing the circuit from the battery 6 to the controller 15. With the elements referred to in the position shown in Fig. 7, the handle 35 15' may be operated in either direction to operate the controller 15 and motor 5 accordingly. If the operative removes his foot from the pedal 8, the elements referred to under the influence of the spring 9 will 40 move in the opposite direction, the thrust member 39 first compressing the spring 36 and putting it under tension, following which the cam 59 operates the plunger 48 to release the reciprocating member 29. 45 Upon the release of the reciprocating member 29, the tension of the spring 36 actuates it with a relatively quick movement to the position shown in Figs. 3 and 6, thereby disengaging the contact 26 from the contact 25 and opening the circuit therethrough. 50 When the contacts are in such position, the controller 15 may be operated by the handle 15', but such operation will be ineffectual. Thus it will be seen that the elements 55 described herein are correlated to close the circuit by the operation of the foot pedal in one direction, viz, downwardly, and open the circuit by the movement of the foot pedal in the opposite direction.

60 In the foregoing description or explanation of the operations involved in starting and stopping the motor 5 by the manipulation of the handle 15', it has been assumed that the handle 15' and likewise the control-
65 ler 15 were in neutral position at the time

the pedal was pushed downwardly and at the time the pedal was allowed to assume its normal position under the influence of the spring 9. When the handle 15' and controller 15 are in such position, no danger of course exists nor damage results, if an operative or any person purposely or otherwise mounts the platform 4 (or without mounting the platform) and presses the pedal 8 down, as above described. However, it can readily be seen that if the operative through carelessness, or due to falling off or leaving the platform, while the vehicle is in operation—that is with the handle 15' in operated position—allowed the pedal 8 to assume its normal position, thereby breaking or opening the circuit through the contacts, and thereafter the operative or any other person with the intention of operating the vehicle or for other reasons, pushed the pedal 8 downwardly, the motor 5 would be set in operation, the wheels 2 rotated and the truck driven forwardly or backwardly with possible resulting damage to the truck or adjacent objects. Such conditions might also arise if some one moved the handle 15' to one of its operated positions and thereafter the operative (without first moving the handle to neutral position) boarded the platform 4 and operated the pedal 8. To prevent accidents and damage which would result, as above set forth, I provide the mechanism 58, already referred to. Of this mechanism, 71 indicates a ring fixed to and revolved by the shaft 15^a of the controller 15. At one point in its circumference the ring 71 is provided with a cam 72 which acts on one end of a slide 73 mounted in an opening 74 formed in the base board 15^b of the controller 15 and a collar 75 fixed to the outer face of the base board. The other end of the slide 73 engages one arm of a bell crank 76, pivoted on a bracket 77 which is also fixed to the base board 15^b. The other arm of the bell crank 76 is operatively connected to the lower end of a rod 78. The upper end of the rod 78 is operatively connected to a socket member 79, adjustably fixed to the outer end of a lever 80. The lever 80 is mounted on a pivot 81, preferably carried by one end wall 18^c of the casing 18. The inner end of the slide 73 is provided with a roller 73' which rides on the circumferential edge of the ring 71 and cam 72. The cam 72 is so arranged angularly of the axis of the controller drum shaft 15^a that when the controller 15 is in neutral position, the cam 72 will be in the position shown in Fig. 2 and the slide 73 will be moved to its outer position and the rod 78 and lever 80 will be elevated, as shown in Figs. 10 and 11, but if the controller 15 is operated in either direction, the movement of the cam 72 with the drum will permit the slide 73 to move inwardly, such operation taking place due to the gravitation of the

rod 78, socket 79 and lever 80. 82 indicates a plunger mounted in a recess 83 formed in the extended adjacent end of the casing member 49. The plunger is formed with bifurcations 84 which permit it to straddle the lock and release rod 54 and the free ends of the bifurcations to engage the lever 80. The plunger 82 is preferably formed with a socket 85 to receive one end of a coiled 10 spring 86. The other end of the spring engages the bottom wall of the recess 83. The spring 86 tends to push the plunger 82 downwardly, it being compressed by the plunger 82 when the latter is elevated by the lever 80, as shown in Figs. 2, 3, 10 and 11, and supplementing the weight of the rod 78 and the elements associated therewith to move the slide 73 inwardly when the cam 72 is moved by the controller drum shaft 15. 20

When the cam 72 is thus moved, the plunger 82 is allowed to be actuated by the spring 86 downwardly to the position shown in Figs. 11 and 12, in which position the body 25 portion of the plunger will be disposed in the path of movement of a shoulder or up-standing member 87 carried by the rod 54, so that through the engagement of the shoulder 87 with the plunger 82, the rod 54 will 30 be maintained inoperative, viz; prevented from moving endwise toward the right as viewed in Fig. 13 far enough for the cam 60 to operate the plunger 48. Accordingly, the reciprocating member 29 will be maintained in its locked position with the contacts separated, as shown in Fig. 16. The parts or elements just referred to assume the positions shown in Fig. 11 at each operation of the controller in either direction; accordingly, if after the controller is operated, the pedal 8 is allowed to move upwardly, due to reasons heretofore set forth, it will be impossible to close the circuit through the contacts 25, 26, due to the locking of the rod 54 against movement as just described, and such inoperative condition will exist until the controller 15 is returned to neutral position, this latter operation serving through the cam 72, slide 73, lever 76, rod 78 and lever 80 to move the plunger 82 out of the path of movement of the shoulder 87. With the parts in the positions described, should attempt be made to push the pedal 8 downwardly, the thrust member 39 will compress the spring 37 and will also move relative to the rod 54 (after the latter is arrested by the plunger 82), such relative movement being permitted by the spring 67—see Fig. 13.

88 indicates ducts formed in the walls of the casing 18—only one being shown—and leading to the guides or walls for slidably supporting the reciprocating member 29 and rod 54 for conducting a lubricant thereto. 60

65 The openings 88 are closed by closing de-

vices 89 which permit the lubricant to be injected into the ducts 88.

90, 91, indicate a pair of auxiliary contacts, formed from carbon and carried by the contacts 25, 26, respectively; the provision of these contacts being for the purpose of preventing arcing when the contacts 25, 26, are separated. The contact 91 is rigidly supported in an opening formed in the block 27. The contact 90 is slidably mounted in a tubular member 92 preferably formed integrally with the block 25^a of which the contact 25 is a part. The tubular member is flanged at 93 at one end and provided at its opposite end with a removable ring 94 which limits the movement of the contact. The contact 90 is preferably mounted in a collar 95 which has sliding fit with the inner wall of the tubular member. The contact 90 is removably held in the collar 95 by a cap 96 (having screw threaded engagement with the collar) which also serves as the means for securing one end of a lead 97 to insure an electrical connection from the block 25^a. The contact 90 is rigidly maintained at the left end (as viewed in Figs. 6, 7 and 13) of the tubular member 92 by a coiled spring 98 disposed between and engaging at its opposite ends the cap 96 and ring 94.

The contacts 90, 91, are so disposed that (1) in the movement of the reciprocating member 29 to close the circuit, they will engage and close the circuit ahead of the engagement of the contacts 25, 26, the spring 98 permitting the contact 90 to be moved by the contact 91 as the reciprocating member 29 moves to its extreme position, as shown in Fig. 7; and (2) in the movement of the reciprocating member in the opposite direction, the disengagement of the contacts 90, 91, will follow the disengagement of the contacts 25, 26; accordingly, the circuit will remain closed through the contacts 90, 91, until after the contacts 25, 26, are completely separated and the circuit opened therethrough, such arrangement and operation insuring a breaking of the circuit without undue arcing.

From the foregoing description it will be seen that I have provided a relatively simple construction in which all the elements are positively operated and controlled. It will also be seen that the elements are correlated with and positively controlled through or in connection with the truck operating elements, namely, the foot pedal 8 and controller handle 15', which must be operated when operation of the truck is commenced and finished, so that the operative is not required to become trained with the use, function and operation of any additional mechanisms or operating members therefor. Furthermore, the means which prevent the closing of the circuit by the

operation of the foot pedal while the controller is in the "on" position is so correlated with the circuit closing and opening mechanism that they automatically operate at all times to positions which prevent the closing of the circuit and resulting damage in the event abnormal operation of the operating members take place through accident, mistake or carelessness, as herein set forth.

10 To those skilled in the art of making mechanism of the class described, many alterations in construction and widely differing embodiments and applications of my invention will suggest themselves without departing 15 from the spirit and scope thereof. My disclosures and the description herein are purely illustrative and are not intended to be in any sense limiting.

What I claim is:

20 1. In apparatus of the class described, the combination of a controller interposed in and movable to close and open an electric circuit, a movable member, a pair of contacts, one of said contacts being carried by said 25 movable member and arranged to engage and disengage the other contact, means for operating said movable member, means for locking said member against movement in either direction, means for releasing said locking 30 means when said operating means are actuated, and means for preventing operation of said releasing means in the event said movable contact is disengaged from said other contact and said controller is in circuit closing 35 position.

2. In apparatus of the class described, the combination of a controller interposed in and movable to close and open an electric circuit, a movable member, a pair of contacts, one 40 of said contacts being carried by said movable member and arranged to engage and disengage the other contact, means for operating said movable member, means for locking said member against movement in 45 either direction, means for releasing said locking means when said operating means are actuated, and means for preventing operation of said releasing means, whereby said movable member remains locked against 50 movement in one direction, the operation of said preventing means being dependent upon said controller being in the circuit closing position.

3. In apparatus of the class described, the 55 combination with an electric circuit and a controller therefor, of a pair of contacts interposed in said circuit, one of said contacts being movable and arranged to engage and disengage the other contact, a movable member, connections between said member and said movable contact for operating the latter, means for locking one element of said connections against movement in either direction, means for automatically operating said 60 locking means to release the locked element

of said connections, and means for maintaining said automatically operating means against movement in one direction in the event the circuit is broken through said contacts with said controller in its operated 70 position.

4. In apparatus of the class described, the combination of a pair of contacts through which an electric circuit to a controller is opened or closed, a pair of reciprocatable 75 slide members connected to move together, one of said members carrying one of said contacts, means for locking said contact carrying member against movement in one direction, a device carried by the other member for releasing said locking means, means for operating said members in either direction, and means operable when said controller is in operated position for maintaining 80 said device carrying member inoperative if the electric circuit through said contacts is opened.

5. An apparatus as described in claim 4 in which the connections between the said slide members permit relative movement between them in one direction when said device carrying member is maintained inoperative.

6. In apparatus of the class described, the combination of a controller, a pair of contacts through which an electric circuit to 95 said controller is opened and closed, a pair of reciprocatable slide members connected to move together, one of said members carrying one of said contacts, means for locking said contact carrying member against movement in one direction, a device carried by the other member for releasing said locking means, means for operating said members in either direction, means normally tending to engage said device carrying member to hold 100 it against movement in one direction, and mechanism actuated by said controller for maintaining said holding means inoperative when the controller is in neutral position.

7. An apparatus as described in claim 6 110 in which the mechanism for maintaining the holding means inoperative includes a cam fixed to the controller shaft.

8. In apparatus of the class described, the combination of a controller, a pair of contacts through which an electric circuit to 115 said controller is opened and closed, a reciprocatable member which carries one of said contacts, means for locking said member against movement in either direction, a pair 120 of compression springs carried by said member, a thrust element interposed between and engaging one of said springs to compress it when moved in either direction, means for moving said thrust element, means connected to and moved by said thrust element moving means for releasing said contact carrying member after one of said springs has been compressed, and devices for locking 125 said releasing means against movement 130

in one direction when the circuit through said contacts is open and said controller is in the "on" position.

9. In apparatus of the class described, the combination of a controller, a pair of contacts through which an electric circuit to said controller is opened and closed, a reciprocatable member which carries one of said contacts, means for locking said member against movement in either direction, a pair of compression springs carried by said member, a thrust element interposed between and engaging one of said springs to compress it when moved in either direction, means for moving said thrust element, means connected to and moved by said thrust element moving means for releasing said contact carrying member after one of said springs has been compressed, and devices for locking said releasing means against movement when the circuit through said contacts is open and said controller is in the "on" position, said devices being moved to an inoperative position when the controller is returned to neutral position.

10. In apparatus of the class described, the combination of a controller, a pair of contacts through which an electric circuit to said controller is opened and closed, a reciprocatable member which carries one of said contacts, means for locking said member against movement in either direction, a pair of compression springs carried by said member, a thrust element interposed between and engaging one of said springs to compress it when moved in either direction, means for moving said thrust element, means connected to and moved by said thrust element moving means for releasing said contact carrying member after one of said springs has been compressed, devices for locking said releasing means against movement when the circuit through said contacts is open and said controller is in the "on" position, and a cam on the shaft of the controller for moving said locking devices into an inoperative position when said controller is moved to neutral position.

11. In apparatus of the class described, the combination with a controller, of a pair of movable members, means for locking one of said members, a pair of contacts through which an electric circuit to said controller is closed, one of said contacts being carried by that member that is engaged by said locking means, means carried by the other member for operating the locking means to release said contact carrying member, means dependent on the position of said controller for preventing movement of said other member in one direction, and means for moving said members.

12. An apparatus as described in claim

11 in which the operating means for said members include yieldable connections with each thereof.

13. In apparatus of the class described, the combination with an electric circuit, of a pair of switch mechanisms interposed in said circuit, means for manually operating said mechanisms independently, means associated with the operating means for one of said mechanisms for locking and automatically releasing one movable element thereof, and means dependent upon the operation of one movable element of the other switch mechanism for preventing operation of the releasing element of said locking and releasing means.

14. In apparatus of the class described, the combination with an electric circuit, of a controller interposed in said circuit and having a movable element, a switch mechanism interposed in said circuit and having a movable element, means for manually operating said controller and said mechanism independently, means associated with the operating means for said mechanism for locking and automatically releasing the movable element thereof, and means dependent upon the operation of the movable element of said controller for preventing operation of the releasing element of said locking and releasing means, said preventing means normally tending to move into an operative position and arranged to be moved into an inoperative position by the movable element of said controller when the latter is in circuit opening position.

15. In apparatus of the class described, the combination with a controller, of a pair of contacts, a pair of movable devices one of which carries one of said contacts to move it into and out of engagement with the other contact, a pair of plungers each arranged to engage the contact carrying device to lock it against movement in one direction, cam means carried by the other device and arranged to actuate that plunger which is in locking engagement with said contact carrying device to release the latter when moved, means for operating said movable devices, and means under the control of said controller and arranged to lock the cam means carrying device against movement in one direction to prevent release of said contact carrying device and operation of the latter to move the contact carried by it into engagement with the other contact.

16. In apparatus of the class described, the combination with a controller, of a pair of contacts, a pair of movable devices one of which carries one of said contacts to move it into and out of engagement with the other contact, a locking means for each of said movable devices, one of said locking means being operatively connected with said con-

- troller and controlled thereby for locking and releasing the other movable device, and means carried by said other movable device for controlling the locking and release of 5 said contact carrying device.
17. In apparatus of the class described, the combination with a controller, of a pair of contacts, a pair of movable devices one of which carries one of said contacts to move it into and out of engagement with the other contact, a locking means for each of said movable devices, one of said locking means being operatively connected with said controller and controlled thereby for locking and 10 releasing the other movable device, means carried by said other movable device for controlling the locking and release of said contact carrying device, and means for operating said devices in opposite directions.
18. In apparatus of the class described, the combination with a controller, of a pair of contacts, a pair of movable devices one of which carries one of said contacts to move it into and out of engagement with the other contact, a locking means for each of said movable devices, one of said locking means being operatively connected with said controller and controlled thereby for locking and releasing the other movable device, 15 means carried by said other movable device for controlling the locking and release of said contact carrying device, and means for operating said devices in opposite directions, said operating means including yieldable connections with each of said devices whereby said operating means may move relative to said devices when said other device is locked against movement.
19. In apparatus of the class described, the combination with a controller, of a pair of contacts, a pair of movable devices one of which carries one of said contacts to move it into and out of engagement with the other contact, a locking means for each of said movable devices, cam means operated by 20 the other device for releasing said locking means from said contact carrying member, and cam means operated by said controller for controlling the locking means for said other device. 25
20. In apparatus of the class described, the combination with a controller, of a pair of main contacts, a pair of movable devices one of which carries one of said contacts to move it into and out of engagement with the other contact, a pair of plungers each arranged to engage the contact carrying device to lock it against movement in one direction, means carried by the other device and arranged to actuate that plunger which 30 is in locking engagement with said contact carrying device to release the latter when moved, means for operating said movable devices, means under the control of said controller and arranged to lock said other device against movement in one direction to prevent release of said contact carrying device and operation of the latter to move the contact carried by it into engagement with the other contact, and auxiliary contacts connected with said main contacts respectively and positioned to engage each other in advance of said main contacts and to disengage each other following the disengagement of said main contacts. 35

In testimony whereof I affix my signature.

EDWARD H. REMDE.
